[57] ABSTRACT

There is disclosed a thermostatic switch consisting es-

sentially of a tubular casing formed of a material having a relatively high coefficient of expansion and a circuit controlling member which is disposed therein and formed of a pair of metallic springs having a relatively low coefficient of expansion. This thermostatic switch is provided with means which permits the accurate response to the ambient temperature change i.e., means such as for preventing so called backlash or minute gap caused at the thread-engaging portions between the circuit controlling member and the casing, and it is provided with means which aids in enhancing the heat sensing of the circuit controlling member in co-operation with the sensing of the casing. In another aspect of the invention, there are provided means which can protect the lead wires connected to the circuit controlling member and the temperature adjusting lock screw from erroneous operations caused by inadvertent contact with or impingement on other moving substance such as a body or the like.

THERMOSTATIC SWITCH

BACKGROUND OF THE INVENTION

This invention relates to a thermostatic switch which utilizes the difference in the coefficient of the expansion between two kinds of metals.

A known thermostatic switch of a type disclosed herein consists essentially of an outer casing formed of a material having a relatively high coefficient of expansion and adapted to directly sense the ambient temperature change, and of a circuit controlling member disposed therein and formed of a pair of metallic springs having a relatively low coefficient of expansion. The circuit controlling member usually has means to permit the thread-engagement with one end of the outer casing. More particularly, the circuit controlling member has a stud longitudinally extending therefrom which has a threaded end portion that in turn is received in an interiorly threaded hole of a sleeve. The sleeve has an exteriorly threaded outer surface which is in thread-engagement with a threaded hole in one end wall of the casing and usually protrudes outwardly from the end wall of the casing.

Electric lead wires are connected to electric contact members which are carried on the two opposing spring members respectively and usually are directed outwardly through the closure of the casing.

Furthermore, there is usually a certain amount of space inside the casing around the circuit controlling members, which somewhat retards the heat sensing of said controlling member as compared with the sensing of the outer casing.

In a thermostatic switch of a type which has been described above, some disadvantages are encountered in practical use, such as:

a. the backlash is likely to take place at thread-engagement between said stud and said sleeve, because, when the ambient temperature is raised, the sleeve portion expands to a greater extent than the stud portion of the circuit controlling members, thus causing backlash or a minute gap between the interior threads of the sleeve and the exterior threads of the stud portion, such that there is introduced some degree of delay in responding to the ambient temperature change;

b. because of the existence of somewhat excessive space around the circuit controlling members in the casing, the heat transmission to said controlling members through said casing is somewhat retarded;

c. the lead wires from the electric contact members in the casing to the outside are likely to be subject to inadvertent handling such as being pulled carelessly, thereby resulting in the erroneous operation of the switch; and

d. because of the sleeve protruding outwardly from the end wall or closure of the casing for adjustment of the temperature setting, there is a risk of the sleeve impinging or contacting some other moving body, thereby resulting in the erroneous operation of the thermostatic switch.

It is accordingly an object of the invention to provide a thermostatic switch which is substantially free from such backlash at the thread-engaging portions between said stud and the sleeve and between said stud and the end wall of the casing.

It is a further object of the invention to provide a thermostatic switch which minimizes the retardation of

the heat sensing function of the circuit controlling member with respect to the sensing of the outer casing of the switch.

It is a still further object of the invention to provide a thermostatic switch which can substantially eliminate the erroneous operation caused by the inadvertent handling of the lead wires.

It is a yet further object of the invention to provide a thermostatic switch which can substantially reduce the erroneous operation of the thermostatic switch due to the inadvertent handling of the temperature setting sleeve.

SUMMARY OF THE INVENTION

15 According to the present invention, there is provided a thermostatic switch which consists essentially of an outer casing and circuit controlling member as have been described, said controlling members having at one end a stud extending therefrom through an end wall of the casing to the outside and a compression spring mounted at its other end intermediate the other end of the controlling member and the other end wall of said casing to thereby maintain said circuit controlling member in tension, thus precluding the possible backlash at the thread-engaging portions between said stud and the sleeve and between said sleeve and the end wall of the casing.

The thermostatic switch further incorporates clamp means mounted on the circuit controlling member to rigidly secure the lead wires thereto, thus precluding the influence of the external stress which may inadvertently be exerted from outside, such as by pulling the lead wires.

Still furthermore, the thermostatic switch of the invention features the heat conductive member of a hollow cylindrical form which is provided as a layer of aluminum foil copper foil or the like and it serves as a liner along the inner wall of said casing, thus narrowing the space between the circuit controlling member and the inner wall of the casing, such that the temperature change will be more efficiently transmitted through the wall of the casing to the circuit controlling member, presenting improved heat sensing functions between the two.

45 In addition to these, the thermostatic switch of the present invention incorporates a locking means adapted to be mounted around said protruding sleeve from both sides so as to insure the rigid mounting of the stud on the end wall of the casing and to protect the sleeve from the influence of external, inadvertent stress application, coupled with the purpose of providing a consistent temperature setting of the circuit controlling member.

BRIEF DESCRIPTION OF THE DRAWINGS

FIG. 1 is a longitudinal elevational view partially in section of one embodiment of the thermostatic switch of the present invention;

FIG. 2 is a fragmentary perspective view partially broken away of one end portion of a supporting member for the circuit controlling member used in the present invention;

FIG. 3 is a transverse cross sectional view taken at points A—A of FIG. 1;

FIG. 4 is an exploded perspective view of a locking means for the adjusting screw or temperature setting sleeve of the present invention;

FIG. 5 is a longitudinal elevational view partially broken away and partially in section illustrating another feature of the thermostatic switch of the invention;

FIG. 6 is an enlarged fragmentary sectional view showing the thread-engagement of the sleeve of FIG. 5;

FIG. 7 is a longitudinal elevational view partially in section illustrating another feature of the thermostatic switch of the present invention;

FIG. 8 is a transverse cross sectional elevational view taken at points B—B of FIG. 7;

FIG. 9 is a fragmentary perspective view partially in section illustrating the lead wires being directed through the holes provided in one end wall or closure of the casing;

FIG. 10 is a longitudinal elevational view partially in section of a still further feature of the thermostatic switch of the present invention wherein a heat conductive member or liner is mounted along the inner wall of the casing; and

FIG. 11 is a schematic diagram illustrating the principle of the backlash caused at the points of thread-engagement between the stud and the sleeve, and between the sleeve and the end wall of the casing;

DETAILED DESCRIPTION OF THE INVENTION:

Referring now to FIG. 1 the reference numeral 1 generally designates a heat sensing casing of a tubular form, an end wall or closure 2 and a stem portion 3 integral with the end wall. A head 4 is formed on the stem 3 and a compression spring 5 is positioned on the stem beneath the head. A circuit controlling member 6 is provided and includes a pair of electric contact plates 7. Insulating members 8 are wound around the mid-portions of the contact plates, said insulating members being made of a material such as mica. Electric contact mounts 9 and electric contacts 10 are secured to the plates 7. A supporting member 11 is adapted to support one end of the contact plates 7 and a similar supporting member 12 is adapted to support the other end of the contact plates 7. A stud or electric contact opening and closing member 13 extends through the supporting member 12 and is secured thereto by a locking member such as a nut 14. Notches are provided in the opposite sides of the supporting member 12 to receive guide ribs 16 that extend longitudinally along the inner wall of the casing 1. The stud 13 has exterior threads 17 that are positioned within the outer end wall or closure 18 of the casing 1 in an interiorly threaded hole 19. A temperature setting or adjusting threaded sleeve or screw 20 which has an exteriorly threaded portion 21 is adapted to be threaded in the threaded hole 19. The interior of the sleeve 20 is threaded and is adapted to threadingly receive the exteriorly threaded portion 17 of the stud 13 therein.

The reference numeral 23 designates a pair of tapered holders of frusto-conical shape which is divided into two portions, each having a curved surface of semi-circular cross section. A clamping ring 26 is adapted to fit over the curved, outer surfaces 24 of the frusto-conical portions 27. Elongated screws 28 are used to urge said frusto-conical portions against the outer face of the end wall 18. The numerals 29 in FIG. 4 designate holes for receiving the end of the screws 28 therein.

As shown in FIG. 8 lead wires 30 and lead wire clamping members 31 are secured to the supporting member which has a guide portion 32 having a hole 34

(FIG. 6) of the same diameter as the outer diameter of the sleeve 20. FIG. 6 also illustrates that the end wall is provided with an enlarged annular groove 33. The guide portion 32 extends integrally from the end wall or closure 18. Holes 35 (FIG. 9) are provided to pass the lead wires and spiral lead wire guides 36 therethrough.

Referring to FIG. 10, there is shown a heat conductive layer or liner 37 mounted along the inner wall of the casing 1, the liner being formed of metal foil having high heat conductivity, such as aluminum foil or copper foil.

In FIG. 11, there is shown a schematic diagram in which the reference numerals 17 and 21 are the exteriorly threaded portions of the stud 13 and the sleeve 20, respectively, while the numerals 22 and 19 are the interiorly threaded portion of the sleeve 20 and the hole 19, respectively.

FIG. 11 illustrates that there arises a minute gap between the meshing threaded portions due to the heat influence, i.e., so called backlash phenomenon.

As is now clear from the reading of the description given thus far, the backlash, which is likely to take place at the points of thread-engagement between two meshing threaded portions such as the combination of the threaded portions 17 and 22 and that of 21 and 19, is prevented by the provision of the spring 5 interposed between the head 4 and the supporting member 11, said spring being adapted to maintain the circuit controlling member 6 in tension so as to eliminate such a backlash or minute gap between the meshing threaded portions.

The lead wires 30 are clamped on to the supporting member 12 by means of the clamping members 31 so as to block the force being exerted exteriorly, and furthermore the lead wires 30 are protected from wear or rubbing by means of the spiral wire guide 36.

As shown in FIG. 10, because of the provision of the heat conductive layer 37, the space around the circuit controlling members is lessened, so that the heat transmitted through the wall of the casing (1) is efficiently transmitted through the heat conductive layer 37 inwardly, thus bringing the circuit controlling members into well co-operated relation to the outer casing in the sense of the heat sensing or responding capability.

As shown in FIGS. 1 and 5, the protruding sleeve 20 or temperature setting-adjusting screw is embraced from both sides by the frusto-conical members which are shown as being divided into two identical portions 23 and 23. The frusto-conical members 23 are received in the clamping ring 26 which is pushed towards the end wall 18 by means of the elongated screws 28. Accordingly, the threaded sleeve 20 is held rigidly against the end wall 18, thus eliminating the centering deviation thereof. The sleeve 20 will be further firmly held within the frusto-conical members 23, if the inner wall of the hole formed in said frusto-conical member 23 is knurled. To improve the centering of the sleeve 20 being received in the end wall 18, there is provided an extended sleeve portion or a guide portion 32 as shown in FIG. 6.

As is apparent from the foregoing, the disadvantages experienced with the conventional type thermostatic switch of a type similar to that of the present invention, as referred to earlier under the paragraphs (a) through (d), can be avoided by the provisions of the spring 5, the lead wire clamping members 31, the heat conduc-

tive layer 37 and the locking means consisting of frusto-conical members 23, the clamping ring 26 and the elongated screws 28.

The detailed description of the functions of the known parts of the thermostatic switch are specifically omitted, because these are self-explanatory to those skilled in the art.

It will be understood that this invention is not limited to the details given herein but that it may be modified within the scope of the appended claims.

What is claimed is:

1. In a thermostatic switch having a tubular casing formed of a relatively high coefficient of expansion material and including an internally positioned circuit controlling member formed of a pair of metallic springs having a relatively low coefficient of expansion, lead wire means extending outwardly of said casing from the circuit controlling member and means extending outwardly of said casing for adjusting the circuit controlling member, the improvement comprising the combination of:

a compression spring mounted between one end of the circuit controlling member and a portion of the casing;

locking means adapted to embrace the externally located portion of the adjusting means, said locking means comprising an axially split, frusto-conical member, a clamping ring positioned over the outer surface of said split, frusto-conical member and screws passing through said clamping ring and threaded into the casing for pulling said split frusto-conical member together and toward the end wall of the casing; and

10 means for clamping the lead wire means on the circuit controlling member.

2. The thermostatic switch as set forth in claim 1 including the further improvement of a heat conductive layer on the interior surface of the casing.

15 3. The thermostatic switch as set forth in claim 2 wherein said heat conductive layer is formed of copper foil.

4. The thermostatic switch as set forth in claim 2 wherein said heat conductive layer is formed of aluminum foil.

20 5. The thermostatic switch as set forth in claim 1 including the further improvement of spiral guide means for protecting the lead wires.
